UNITED STATES PATENT OFFICE.

SAMUEL L. MARKS, OF NEW YORK, N. Y.

HOTEL AND TRAVELER'S DIRECTORY-CABINET.

1,357,464.

Specification of Letters Patent.

Patented Nov. 2, 1920.

Application filed April 9, 1919. Serial No. 288,846.

To all whom it may concern:

Be it known that I, SAMUEL L. MARKS, a citizen of the United States, residing at New York city, in the county of New York and State of New York, have invented certain new and useful Improvements in Hotel and Travelers' Directory-Cabinets; and I do hereby declare the following to be a full, clear, and exact description of the invention, such as will enable others skilled in the art to which it appertains to make and use the same.

This invention relates to a directory cabinet for use in the guest chambers or public rooms of hotels or rooming houses or for use on all vehicles of transportation, ashore or afloat. This, of course, includes such carriers as railroads, steamships, etc.

The object of the invention is to provide a directory for the public in a very attractive and compact form so the invention consists essentially of a cabinet having a series of index plates supported from the face of the cabinet and connected to withdrawable curtains that are spring-actuated. The index plate has stamped on it the general classification of the information contained on the curtain, such as "Theaters" and on the curtain would appear the information about the various theaters that are vouchered for by the hotel that displays this cabinet. The plan of use of this cabinet is to charge the individual advertisers for having their business cards or advertisements appear on a curtain in this cabinet which, of course, must be satisfactory to the hotel that equips its rooms with these cabinets and the hotels may be charged for the use of these cabinets or they may be sold outright to the hotels. To agree to let a chain of hotels in one locality have the exclusive right to use these cabinets would probably bring a greater income.

The invention is illustrated in the accompanying drawings, in which

Figure 1 shows a front elevation of the cabinet.

Fig. 2 is a plan view thereof.

Fig. 3 is a partial side elevation of the cabinet with parts in section.

Fig. 4 is a sectional view taken along the line 4—4 of Fig. 2.

Fig. 5 is a sectional view taken along the line 5—5 of Fig. 2.

Fig. 6 is a sectional view taken along the line 6—6 of Fig. 1, and

Figs. 7 to 10 show partial views of details.

In the drawings, numeral 11 indicates the cabinet having a front face plate 12, side plates 13, an elongated base 14 which is adapted to contain a pen compartment 15. The cabinet 11 is inclined backwardly in relation to the base 14. 16 indicates the back of the cabinet.

On the face of the cabinet 12 are located one or more tiers of index plates 17, each provided with a knob or pull 18 located in the lower portion of the index plate 17 in order not to obstruct the view of the legend 19 carried by the index plates indicating the general character of information carried on the curtain connected with that particular index plate.

19 represents a flexible curtain and 20 a spring-actuated roll upon which curtain 19 is adapted to be wound. The end of the curtain 19 is bent back upon itself at 20 and has clamped thereover a connector 21 having two oppositely directed inclined faces 22 and 23 and is provided with a vertical face equipped with slots 24. Headed pins 25 are provided on the rear of the index plate 17, adapted to coact with the slots 24 to removably fasten the index plates 17 to the connectors 21. The connectors 21 pass in through slots 26 in the face 12 of the cabinet and the inclined sides 22 and 23 thereof engage with the edges of the slots 26 to center the index plates 17 with relation to the slots 26.

The sides 13 of the cabinet are equipped with indented spring edges 27 adapted to engage in detents 28 and 29 in the back and front plates respectively with the cabinet to removably hold the sides in place. A frame 30 is carried within the cabinet and removable therefrom when the sides 13 are not in place. 31 indicates inclined slots in the rear standards of the frame 30 for holding the spring-actuated rollers 20 in such position that the curtains 19 can be withdrawn from its corresponding slot 26 in the face plate 12.

In operation, if the hotel guest or other person desires to learn what are the points of interest that should be taken in, it is only necessary to withdraw the index plate labeled "Points of interest" by taking hold of the pull 18, by exerting pulling pressure upon the tab 18. This unwinds and withdraws the curtain 19 carried by that index

plate and on the curtain, the visitor sees a directory of the points of interest. As soon as the visitor is satisfied, the pulling pressure is released and the spring-actuated 5 roller causes the curtain to be retracted into the cabinet and the inclined faces of the connector 21 co-act with the edges of the slot 26 to maintain the index plate 17 in centered position with relation to the slot.

10 Where the curtains carry advertisements, it will be desirable to change them from time to time. In order to do this, the side 13 of the cabinet is removed by a pulling pressure sufficient to disengage the edges 27 from the 15 detents 28 and 29. This exposes the frame 30 with its rollers and curtains. The operator takes hold of the curtain or connector 21 with one hand and slides the index plate 17 to the left to disconnect it from the connector whereupon the curtain is wound up entirely upon the roller. This is repeated with 20 each curtain until they are all free from the index plates and then the frame 30 with all the curtain rolls is withdrawn from the cabinet through the open side. New curtains and rolls can then be put in the frame 30, the frame replaced, the connectors threaded 25 through the slots 26 and the proper index plates attached to the connectors. The connectors 21 are removable from the curtains 30 by sliding laterally but it may be found desirable not to remove them from the curtains when they are being changed.

The cabinet as shown in the drawings is 35 provided with an ink stand between the tiers of indexes and, of course, two stands may be used if desired instead of one. Over the stand is indicated a calendar for which a scratch pad may be substituted or various 40 other articles may be used. The tiers of indexes may be used singly, doubly as shown, or in several combinations. The indexes may be used separately and independently of the cabinet itself if preferred.

The gist of the invention is the providing 45 of a cabinet having main classifications of directories or directories with sub-divisions thereon so that it would be within the spirit of this invention if a book, having main and sub-divisions, as above specified, there- 50 in, be placed upon the cabinet in substitution for the present curtains.

What I claim as my invention is:

1. A hotel and traveler's directory cabinet having in combination a removable directory mechanism including index sheet carrying rolls; a body portion adapted to house the directory mechanism, detents on the sides of the body, removable sides for the body, and indented spring edges on said 60 sides adapted to engage said detents whereby the sides are removably held on said body portion.

2. A device of the class described having a body portion, a face plate carried thereby 65 having interrupted slots therein, said slots extending inwardly from the outer edge of the face plate, curtains carrying advertisements in said body portion, index plates connected to the curtains supported from the 70 slots in the face plate, and a removable side cover for the body portion having inturned edges adapted to cover the outer ends of the slots.

3. A device of the class described having 75 a body portion, a face plate carried thereby having interrupted slots therein, curtains carrying advertisements in said body portion, index plates larger than the slot openings, and a separable connector between each 80 curtain and its index plate.

4. The device of claim 4 in which the connector supports the index plate.

5. The device of claim 4 in which the connectors have inturned edges for gripping the 85 curtain.

In testimony whereof I affix my signature.

SAMUEL L. MARKS.
